(57) **CLAIM**

The ornamental design for a large shipping crate for small live animals, as shown and described.

DESCRIPTION

FIG. 1 is a top perspective view of a large shipping crate for small live animals providing a high air flow and being stackable showing a first embodiment of my new design.

FIG. 2 is a bottom perspective view thereof.

FIG. 3 is a top plan view thereof.

FIG. 4 is a bottom plan view thereof.

FIG. 5 is a right side elevation view thereof.

FIG. 6 is a left side elevation view thereof.

FIG. 7 is a front elevation view thereof.

FIG. 8 is a rear elevation view thereof.

FIG. 9 is a top perspective view of a large shipping crate for small live animals providing a high air flow and being stackable showing a second embodiment of my new design.

FIG. 10 is a bottom perspective view of the embodiment of FIG. 9.

FIG. 11 is a top plan view of the embodiment of FIG. 9.

FIG. 12 is a bottom plan view of the embodiment of FIG. 9.

FIG. 13 is a right side elevation view of the embodiment of FIG. 9.

FIG. 14 is a left side elevation view of the embodiment of FIG. 9.

FIG. 15 is a front elevation view of the embodiment of FIG. 9.

FIG. 16 is a rear elevation view of the embodiment of FIG. 9.

FIG. 17 is a top perspective view of a large shipping crate for small live animals that includes a bird perch in the interior and also provides a high air flow and being stackable with the lid not present, showing the first embodiment of FIG. 1 of my new design; and,

FIG. 18 is an exploded perspective view of a large shipping crate for small live animals that shows a bird perch to be placed in the interior and lid on top when it closed, the cage providing a high air flow and being stackable according to the first embodiment of my new design as shown in FIG. 17. The broken lines showing in the various figures of large shipping crate for small live animals are included for the purpose of illustrating portions of the article that from no part of the claimed design. Shading lines shown in the drawings are intended to represent the approximate three-
